UNITED STATES PATENT OFFICE.

ROY S. BIGELOW, OF CHICAGO, ILLINOIS, ASSIGNOR TO GOODMAN MANUFACTURING COMPANY, OF CHICAGO, ILLINOIS, A CORPORATION OF ILLINOIS.

DRIER-CAR-HANDLING APPARATUS.

Application filed October 15, 1921. Serial No. 508,600.

To all whom it may concern:

Be it known that I, Roy S. Bigelow, a citizen of the United States, residing at Chicago, in the county of Cook and State of Illinois, have invented an Improvement in Drier-Car-Handling Apparatus, of which the following is a specification.

This invention relates to improvements in apparatus for handling material cars in drier tunnels, and the like, and has for its object to produce a labor-saving apparatus for removing cars from the tunnels after the material has been subjected to heat.

The invention may best be understood by reference to the accompanying drawing illustrating the use of my apparatus as applied to brick manufacture, in which Figure 1 is a fragmentary plan view showing a typical layout of the loading end of a plurality of drying tunnels comprising a brick manufacturing plant.

Fig. 2 is a view in cross-section of a portion of the building shown in Fig. 1, and showing my improved handling apparatus installed therein.

In brick manufacturing plants capable of large production, the following steps of manufacture are usually followed. First the bricks are formed in a molding machine or press, then loaded on flat cars and taken to drier tunnels where they are subjected to a medium heat sufficient for partial dehydration, and then are taken to the kilns where they are burned in the usual manner.

In factories of this kind, a large number of drier tunnels are provided, placed side by side and having tracks running therethrough upon which the flat cars are placed. The cars are usually loaded at one portion of the

factory adjacent the molding machines or presses, and are then rolled upon a transfer car, and transported laterally thereon to a place opposite the tunnel in which the bricks are to be dehydrated. In the drawing, I have illustrated a portion of a typical factory in which a transfer car 1 is mounted on a pair of tracks 2 running at right angles to a plurality of track portions 3, 3, extending into the drier tunnels 4, 4. As usually constructed the tracks 3, 3, are slightly inclined, so that the cars will be assisted by gravity while they are being moved through the tunnels. A section of track 1^a is mounted on the transfer car 1 and is adapted to register with any desired set of tunnel tracks

3, 3. The tunnels 4, 4, are provided with suitable doors 5, 5, which are closed while heat is being applied to the bricks. Any usual means of applying heat to the tunnels may be employed. As already suggested, 60 the bricks are placed on flat cars such as indicated by the numeral 6 and are transported on the transfer car 1 to the entrance to one of the drier tunnels 4 where they are run on the track 3 and loaded into said 65 tunnel. After the tunnel has received its desired capacity of brick cars, the doors 5, 5, are closed. After being dehydrated for a desired period, the tunnel is opened and the 70 brick cars are moved out of the opposite end of the tunnel (not shown in the drawing). The cars are rolled out on tracks forming an extension of tracks 3, 3, beyond the exit at the opposite end of the tunnel where the 75 bricks are allowed to cool in the open air. The cooling tracks are not shown as they form no part of the present invention. From thence the bricks are transported to the kilns for burning.

As heretofore practiced, the brick cars 6, 6, 80 have usually been pushed by hand throughout the cycle of movements above described, that is to say they are pushed on the transfer car 1 and then are pushed on a track section 3 and into one of the drier tunnels 85 4. After they are dehydrated they are again pushed by hand out of the tunnel upon the drying tracks at the opposite end thereof and from thence are pushed to the kilns. It will be understood that the brick cars 90 must be handled very carefully owing to the fact that the bricks are piled on the cars with air spaces between adjacent bricks, as shown in the drawing.

Referring now to my improved apparatus 95 for handling the brick cars, I provide a propelling device, such as an electric locomotive 7, adapted to run on tracks 3, 3, and of proper size to enter the tunnels 4, 4. A travelling crane 8 is hung on a beam 9 arranged transversely of and adjacent the entrances of the tunnels 4, 4, and is provided with a detachable lifting mechanism such as a pair of blocks 10, 10, connected by a bar 10^a adapted to engage a pair of hooks 11, 11, extending upwardly from the locomotive 7 so that the locomotive may be raised and transported laterally to serve all of the tunnels 4, 4. The locomotive is preferably provided with a gathering reel 12 of any 110

suitable construction, and carrying a flexible conductor cable 13 having its end attached to the travelling crane 8 so as to allow the locomotive to travel the length of the tunnels. Said locomotive is provided with a spring bumper device 14 at one end thereof adapted to engage an end of the brick cars 6, 6, so as to push them through and out of the tunnel. The operator's cab 15 is preferably located at the inner end of the locomotive adjacent the bumper device 14. In the embodiment illustrated, said operator's cab is provided with a controller 16 and an operator's seat 17 as shown.

15. The brick cars 6, 6, are preferably pushed into the tunnels by hand. The cars are handled singly and are readily moved, especially where the drier car tracks 3, 3, are inclined in the direction of movement of the cars. The doors 5, 5, are then closed and the bricks are subjected to heat in the usual manner. The usual temperature for dehydration may range from 150° to 400° depending on conditions of manufacture. In the higher ranges of temperature indicated, the lubrication of the brick car bearings is often affected so as to make it difficult to start the cars again when the tunnels are reopened after the heating process. It is desirable to move the entire load of several cars as a unit, and it often requires the assistance of several men working in the high temperature of the tunnel to get the cars started. The main difficulty, therefore, in handling the cars by old methods has been in removing the cars from the tunnel, and it is for this purpose that my improved apparatus is advantageously employed. As before suggested, the locomotive 30 7 is adapted to be lifted by the travelling crane and carried to the tunnel which is to be unloaded. The locomotive is lowered onto the track 3, with the hooks 11, 11, facing outwardly so as to be readily disengaged from the bar 10^a when the locomotive moves forwardly. After the doors are opened, the locomotive is manipulated carefully by the operator so that the spring bumper 14 is gently engaged with the outer end of the brick car 6 nearest the entrance. The brick cars are arranged end to end on the track so that the locomotive pushes the entire train of cars out upon the cooling track at the opposite end of the tunnel. 35 50 In this manner the work of removing the cars from the tunnel may be quickly and easily accomplished with a minimum danger of shock to the cars. The locomotive may be quickly returned to the entrance of the tunnel and the hooks 11, 11, may be automatically reengaged with the bar 10^a in position to be lifted by the crane and carried to the next tunnel which is to be opened. The operator is thus subjected to the heat 55 of the tunnel for a minimum period of

time, and the apparatus is completely removed from the tunnel during the heating process, so as to eliminate danger of corrosion of the metal parts. The system of car handling thus described effects a saving both in labor and time, and increases the production capacity of the drier tunnels.

Although I have shown and described one form in which my invention may be embodied, it will be understood that many other means may be employed for accomplishing the same results, without departing from the spirit and scope of my invention. My improved apparatus may also be advantageously applied to other uses, such as tunnel kilns. I do not therefore wish to be understood as limiting myself to the specific construction or use illustrated herein excepting as specifically limited in the appended claims.

85

I claim as my invention:

1. An apparatus of the class described, comprising a plurality of adjacent tunnels, material cars movable through said tunnels, a traveling crane having an overhead runway arranged transversely of the tunnel entrances, a locomotive provided with a resilient bumper at one end thereof adapted to engage the cars in said tunnels, and detachable suspension means for engaging said crane with said locomotive to lift the latter.

90

2. The apparatus for moving material through a plurality of adjacent tunnels, comprising a travelling crane having an overhead runway arranged transversely of the tunnel entrances, an electric locomotive, detachable suspension means on said crane for lifting said locomotive, a flexible conductor cable adapted to connect said crane with said locomotive in all positions of the latter, and a gathering reel for said cable.

100

3. An apparatus of the class described, comprising a plurality of adjacent tunnels, having tracks therethrough, material cars movable through said tunnels, a locomotive, means for moving said locomotive laterally to register with any of said tunnel tracks, resilient bumper means carried by said locomotive at one end thereof adapted to engage the cars in said tunnels, and a flexible conductor cable adapted to connect said moving means with said locomotive in all positions of the latter.

110

4. The apparatus for moving material cars through a plurality of adjacent tunnels, comprising a travelling crane having an overhead runway arranged transversely of the tunnel entrances, and provided with a vertically movable lifting member suspended therefrom, a locomotive having a centrally disposed connecting member, and means for detachably engaging said lifting member with said connecting member comprising a hook carried by one of said members, and adapted to automatically engage

115

120

125

130

the other of said members when the locomotive is moved out of the tunnel entrance.

5. An apparatus of the class described, comprising a plurality of adjacent tunnels, having tracks therethrough, material cars movable through said tunnels, a locomotive, means for moving said locomotive laterally to register with any of said tunnel tracks, resilient bumper means carried by said locomotive at one end thereof adapted to en-

gage the cars in said tunnels, a flexible conductor cable adapted to connect said moving means with said locomotive in all positions of the latter, and a gathering reel for said cable.

15

Signed at Chicago, in the county of Cook and State of Illinois, this 12 day of October, 1921.

ROY S. BIGELOW.
